US00D878419S

(12) United States Design Patent (10) Patent No.: US D878,419 S
(45) Date of Patent: * Mar. 17, 2020

(54) ELECTRONIC DISPLAY OF A COMPUTING DEVICE WITH ICON

(71) Applicant: Wells Fargo Bank, N.A., San Francisco, CA (US)

(72) Inventor: Brendan Murphy, New York, NY (US)

(73) Assignee: Wells Fargo Bank, N.A., San Francisco, CA (US)

() Term: 15 Years

(21) Appl. No.: 29/651,253

(22) Filed: Oct. 21, 2018
